UNITED STATES PATENT OFFICE.

HAROLD D. GRINNELL, OF PITTSFIELD, MASSACHUSETTS, ASSIGNOR TO THE G. C. A. MANUFACTURING COMPANY, OF PITTSFIELD, MASSACHUSETTS, A CORPORATION OF MASSACHUSETTS.

CLUTCH.

Application filed May 17, 1922. Serial No. 561,718.

To all whom it may concern:

Be it known that I, HAROLD D. GRINNELL, a citizen of the United States, and a resident of Pittsfield, in the county of Berkshire and State of Massachusetts, have invented an Improvement in Clutches, of which the following description, in connection with the accompanying drawings, is a specification, like characters on the drawings representing like parts.

This invention relates to an improved clutch or chuck, the object thereof being to provide a frictional, self-adjusting device of this class designed for application to bodies having a circular or curvilinear outline in cross section. While the invention is not restricted in its application to any particular art or arts and with obvious modifications may be adapted to a great variety of uses, as, for example, to lathes and drills, the particular embodiment herein shown is designed more particularly with reference to its application to electric lamp bulb installing and removing devices wherein my invention is employed as a manually operated clutch medium for gripping the lamp bulb.

Referring to the accompanying drawings illustrating a preferred form of embodiment of my invention:

Fig. 1 is a side elevation showing the device applied to an electric lamp bulb;

Fig. 2, a longitudinal vertical section of the same on the line 2--2 of Fig. 1;

Fig. 3, a cross-sectional top view on the line 3--3 of Fig. 2; and

Fig. 4, a view similar to Fig. 3 illustrating my device as applied to a lamp bulb of irregular or elliptical outline.

My invention comprises a recessed or hollow receptacle or barrel 1, providing an interior chamber 2 enclosed by substantially straight, smooth, and uniformly inclined side walls assuming the formation of an inverted frustum round in outline, the larger or receiving end being open. The chamber 2 is consequently gradually reduced in cross-sectional area from top to bottom, the object thereof being to proportionately increase the grip or pressure of the walls upon the engaged surface of the object or work introduced therein as such object or work advances inward under pressure of the operator or other seating force.

These side walls of the receptacle 1 are

designed to be flexible but inexpandable and may be formed of paper, pressed fibre or other material having the requisite properties as herein disclosed, so as to conform to the outline of the foreign object to the extent of their fixed circumferential measure at any given elevation in their length, but not to stretch or expand. When, for example, the contour of the foreign object is irregular or elliptical in cross section, as illustrated in Fig. 4, the outline of the receptacle is modified by the introduction of such object to measurably conform thereto, being temporarily distorted from its true circular formation in the plane of contact and adapted to resume its normal outline when the object is removed. This property of flexibility increases the extent of the actually engaged portion of the surface of the work. In a device of similar formation having slotted side walls or walls constructed of rubber or other yielding or expandable material, the distortion would result in localized stretching or stressing of its walls at the point or points of irregularity in the object, whereas in the present device distortion at any given point involves distortion of the entire contour of the circumference of the walls in the plane affected and where any increase of pressure resulting therefrom is distributed evenly over all points in the circumference, the actual measurement of the circumference however remaining constant.

While the receptacle 1 of the invention herein illustrated is provided with a smooth interior surface, it is obvious that the functional characteristics and objects of the structure described, may be retained in a receptacle having a modified interior surface, which may be corrugated or otherwise roughened for adaptation to particular classes of objects. It should also be pointed out that it is not in all instances necessarily essential to the operation of my device that the central longitudinal line of the object should be adjusted in true alignment with the axis of my device, but in practice the object may in frequent instances assume a somewhat tilted or relatively inclined position, as, for example, in the case of electric lamp bulbs, to which the present embodiment was particularly but not exclusively designed to be applied.

The receptacle 1 is mounted upon a suit-

able carrier 3, the form of which may be modified to conform to the mandrel, shaft or other support to which it is attached. As herein shown, the carrier 3 is a circular 5 transversely arranged member constructed of wood or other suitable material closing the inner or small end of the receptacle and provided centrally with a recess 4, adapted to receive the nipple 5 of a lamp bulb 11, 10 and also provided at or near its margin with one or more transverse openings 12, 12, which serve as air vents. Depending centrally from the carrier and preferably integral therewith is a stem 13 incased in a 15 metal bushing 14 having tapering side walls.

The receptacle 1 may be secured in any suitable manner to the carrier 3, the means herein shown being a clamp 6 constructed of stiff bailing wire surrounding the receptacle 20 at a point near its lower end, the latter being forced into a suitable annular groove provided on the surface of the carrier and forming a permanent seat for the clamp.

25 In its present embodiment my device is detachably mounted to rotate upon a turning rod or spindle 7 carrying at its outer end a socket-member or false chuck 8 provided with an axial bore to receive the spindle and removably secured thereto by a set-screw 9 extending through a suitable threaded opening provided in its side wall and, preferably, in a reduced portion forming the inner end thereof. Said socket-member 30 8 is provided at its outer end with a well or recess 10 to receive the stem 13, and corresponding therewith in form and dimensions, the latter being suitably tapered to conform to the inclined walls of the recess 10, which is graduated in cross-sectional area. While the frictional engagement of the abutting surfaces of these parts normally offers sufficient resistance to prevent displacement of the clutch or their relative 40 movement during rotation, I prefer to provide auxiliary positive latching means of a suitable and convenient character, such as a press-button 15 mounted to slide in a tubular casing 16 fitted into a suitable transverse recess or opening in the side of the stem 13, said press-button being actuated normally outward under the pressure of an expansion spring 17 and adapted to register with co-incident openings in the bushing 14 and 45 socket-member 8.

50 It should be understood that a series of clutches, each having a receptacle of different capacity adapted to receive an object of corresponding dimensions, but severally provided with carriers having like-sized stem portions, may be employed for attachment to the false chuck 8.

55 In the adaptation of my device to the particular class of objects herein shown, namely to incandescent lamp bulbs 11, the size of

the clutch selected is obviously determined by the general contour and proportions of the lamp upon which it is designed to operate, the clutch being mounted for this purpose upon a spindle or rod 7 of indefinite length adapted to install and remove lamps placed beyond the reach of the operator. The side walls of the clutch when forced over the bulb exert the requisite gripping action necessary to enable the operator to 70 install or remove the lamp from its socket by rotating the spindle.

75 It will be apparent that obvious modifications may be made to the form of my device herein shown without departing from the scope of the invention.

80 I claim as my invention:

1. In a clutch, a body having flexible endless side walls and a frusto-conical receiving chamber, said side walls being effective 85 to distribute localized stresses throughout its circumference without enlarging the measure of the circumference.

2. In a device of the class described, in combination, a support and a work-receiving portion having the formation of a frustum and provided with an interior chamber, the side walls of the work-receiving portion being flexible and inexpandable.

3. In a device of the class described, in combination, a support-engaging portion, and a hollow work-receiving portion carried by said support-engaging portion and having a conical formation and an open receiving end, said side walls being constructed 100 of flexible inexpandable substance.

4. In a device of the class described, in combination, a support-engaging portion and a work-receiving portion having straight sloping side walls and having an open receiving end, the said side walls being flexible and inexpandable.

5. In a device of the class described, in combination, a carrier, a depending extension member on the carrier, a barrel mounted on the carrier, and securing means, said barrel having a conical formation with endless flexible side walls and an open receiving end.

6. In a clutch, in combination, a carrier having a tapering stem member for detachable connection with a support, and a hollow conical body mounted on the carrier and having flexible inexpandable side walls and an open receiving end.

7. In a device of the class described, in combination, a spindle, a socket member mounted on one end of the spindle and having an open receiving end, and a carrier having a circular body-portion and a stem member depending from the body-portion and adapted to fit into said recess in the socket-member, said carrier having flexible inexpandable side walls forming a frustum 125 extending above the carrier.

8. In a device of the class described, in combination, a support, a clutch of frusto-conical formation movably mounted on the support and having a hollow receiving chamber and an open receiving end, said chamber having flexible endless side walls, and means for imparting rotary and reciprocating movements to the clutch.
9. In a device of the class described, in combination, a spindle having a head with an open receiving end, a carrier having a stem member extending into said head, lock-

ing means for detachably securing the carrier to said head, and a clutch member on said carrier.

10. In a clutch, in combination, a perforate carrier and a clutch member mounted on the carrier, said clutch member having an open receiving chamber and flexible in-expansive side walls.

In testimony whereof I have signed my name to this specification.

HAROLD D. GRINNELL.
